DISPLAY CASE

Filed April 7, 1925

Fig. 1.

Patented June 22, 1926.

UNITED STATES PATENT OFFICE.

LEE RIEMAN AND HERBERT A. WILCOX, OF ABILENE, KANSAS; SAID WILCOX
ASSIGNOR TO SAID RIEMAN.

DISPLAY CASE.

Application filed April 7, 1925. Serial No. 21,347.

This invention relates to improvements in store furniture, and is more particularly adapted to a case for displaying merchandise in a neat and sanitary manner.

One of the important objects of the present invention is to provide a display case of the above mentioned character which includes a box and a lid therefor, the box being normally disposed at an angle for displaying the merchandise contained therein, playing the merchandise contained therein, means being provided for facilitating the actuation of the lid to cover or uncover the box simultaneous with the tilting thereof.

A further object of the invention is to provide a display case of the above mentioned character wherein the same is of such construction as to prevent any possibility of the customer obtaining access to the merchandise contained within the box from the front of the case.

A still further object is to provide a display case of the above mentioned character which is of such construction as to enable the same to be readily assembled or disassembled, the same being simple in construction, inexpensive, strong and durable and further well adapted to the purpose for which it is designed.

Other objects and advantages of this invention will become apparent during the course of the following description.

In the accompanying drawing, forming a part of this specification, and in which like numerals designate like parts throughout the same:

Figure 1 is a front elevation of the display case embodying our invention.

Figure 2 is a sectional view taken approximately on line 2-2 of Figure 1, and

Figure 3 is a sectional view taken on line 3-3 of Figure 2.

In the drawing, wherein for the purpose of illustration is shown the preferred embodiment of our invention, the numeral 1 designates generally our improved display case, the same comprising the frame 2. The frame is open at its front and rear, and the sides of the frame gradually taper toward the top as is more clearly illustrated in Figure 2. The top 3 is provided with a longitudinally extending substantially V-shaped shelf 4 and the purpose thereof will hereinafter be more fully described.

Arranged in the lower portion of the frame between the sides thereof is the bag

holder designated by the numeral 5, the same being inclined downwardly toward the front of the frame. The forward end of the bag holder is closed as illustrated at 6 and the top and bottom of the bag holder gradually diverge toward the rear of the frame. As is illustrated more clearly in Figure 2 of the drawing, the top 7 of the bag holder has its rear edge terminating at a point intermediate the front and rear faces of the frame.

A rod 8 extends transversely between the sides of the frame 2 and is preferably located adjacent the rear edge of the top 7 of the bag holder 5. An open top box or receptacle designated generally by the numeral 9 is provided with a depending flange 10 around the edges of the bottom thereof. The side flanges are provided with a pair of aligned notches 11, the same being arranged at a point intermediate the ends of the box or receptacle and preferably slightly off the center. The aligning notches cooperate with the transversely extending rod 8 to pivotally support the box between the sides of the frame and the location of the pivot is such as to cause the box to be inclined downwardly in the position as shown in Figure 2. A handle 12 is provided on the rear end of the box. The lower rear end of the box is cut away as is illustrated in Figure 2. A rod 13 extends transversely across the top of the forward end of the box and the ends of this rod protrude beyond the respective sides of the box. The purpose of this rod will also hereinafter be more fully described.

A lid 14 is provided for the box or receptacle 9, the same being provided with the glass top 15 which is supported in the lid in any well known manner, and enables the contents of the box to be at all times readily visible. The lid is pivotally supported at its rear end on the transversely extending rod 16, the latter being arranged in the upper rear portion of the frame. The upper rear portion of the lid is provided with a sleeve like member to accommodate the pivot rod 16 as is clearly illustrated in the drawing. The sides of the lid are provided with the inturned flanges 18 at their bottom edges and these flanges extend for substantially the full length of the sides of the lid, the same terminating at a point adjacent the rear end of the lid as clearly illustrated in

Figure 2. The inturned flanges 18 provide a track or guide for the respective free ends of the rod 13 which extend transversely across the top of the forward end of the box.

The box being filled with the merchandise to be displayed, is normally in the position as shown in Figure 2 of the drawing, and the lid 14 extends over the open top of the 10 box, thus keeping the contents of the box free from any foreign substance, thus keeping the merchandise in a sanitary condition. As is obvious from the construction illustrated in Figure 1, the merchandise in the 15 box is at all times visible to the customers. However, the lid is arranged on the box in such a manner as to render it impossible for a customer to gain access to the contents of the box from the front of the case. The 20 contents may be obtained from the box by the clerk behind the case.

By grasping the handle 12 and tilting the box so that the rear end thereof moves downwardly while the forward end is raised, 25 the upward movement of the forward end of the box will cause the free ends of the rods 13 to cooperate with the lid causing the latter to be raised or swung on its pivot so that the box and lid will be disposed in 30 the position as shown in the dotted lines in Figure 2. The lid will then in no way interfere with the clerk removing the merchandise from the box, and it is understood of course that when the box is tilted rearwardly, the weight of the merchandise in the 35 box will cause the same to move rearwardly by gravity whereby the rear end of the box will rest on the bottom of the bag holder so that the box will not accidentally return 40 to its normal position during the removal of the merchandise therefrom.

The parts will be returned to their normal positions by pulling upwardly on the handle 12. The downward movement of the forward end of the box will cause the free ends of the rod 13 to move forwardly on the track formed by the inturned flanges 18 whereby the lid will also be simultaneously actuated.

The top 3 provides a means for supporting a scale or the like, and the V-shaped shelf 4 is adapted to accommodate various articles of merchandise which are put up in packages so that the same will be distinctively displayed.

55 The display case embodying our invention may be constructed of any suitable metallic

material, such as sheet iron, brass, copper, aluminum or the like, and the parts are so arranged as to enable the box and lid to be readily removed from the frame whenever 60 it becomes necessary. The lid 14 may be disengaged from cooperative relation with respect to the box by moving the free ends of the rods to the extreme rear end of the lid.

65 While we have shown the preferred embodiment of the invention, it is to be understood that various changes in the size, shape and arrangement of parts may be resorted to without departing from the spirit 70 of the invention and the scope of the appended claims.

Having thus described the invention, what we claim as new is:—

1. A display case comprising a frame open 75 at its front and rear, a box tiltably supported intermediate its ends in said frame and normally disposed in a downwardly inclined display position, a transparent lid for the box supported at its rear end in the 80 frame, and means carried by the forward end of the box and cooperating with the lid for facilitating the raising of the forward portion of the lid so as to uncover the rear end of the box when the latter is disposed in 85 a rearwardly inclined discharge position, said means comprising projections extending from the sides of the forward end of the box adjacent the upper edge thereof, and a track associated with the lid to cooperate 90 with the projections.

2. A display case comprising a frame open 95 at its front and rear, a box tiltably supported intermediate its ends in said frame and normally disposed in a forwardly inclined display position, a transparent lid for said box pivotally supported at its rear end in the rear portion of the frame, and means for effecting the upward swinging movement of the forward portion of the lid for uncovering the rear portion of the box when the latter is disposed in a rearwardly inclined discharge position, said means comprising projections extending laterally from the sides 100 of the forward end of the box adjacent the upper edge thereof, and depending tracks formed on the sides of the lid and on which track said projections are adapted to slide.

105 In testimony whereof we affix our signatures.

LEE RIEMAN.
HERBERT A. WILCOX.
